UNITED STATES PATENT OFFICE.

WILFRID LUMLEY, OF EAST CONNEAUT, OHIO, ASSIGNOR TO THE CONNEAUT COMPANY,
A CORPORATION OF OHIO.

DOME FOR ILLUMINATING-FIXTURES.

980,306.

Specification of Letters Patent.

Patented Jan. 3, 1911.

Application filed January 27, 1909. Serial No. 474,382.

To all whom it may concern:

Be it known that I, WILFRID LUMLEY, a citizen of the United States, residing at East Conneaut, in the county of Ashtabula and State of Ohio, have invented a certain new and useful Improvement in Domes for Illuminating-Fixtures, of which the following is a full, clear, and exact description.

The object of the present invention is to provide an improvement in gas and electric fixtures, more particularly in the large decorative domes used for chandeliers and similar lights.

The invention is directed broadly to a construction of dome which shall be capable of decorative effects equal to or superior to those had by the prior constructions and yet be readily taken apart and packed within a small space, thus decreasing the cost of storage and shipment.

It has further been my object to achieve the above described results without impairing the rigidity or strength of the dome in any manner.

The above named advantages and other desirable ends, it will be seen, are obtained by the invention which I have produced, an embodiment of which is described in the following specification with reference to the accompanying drawings in which:

Figure 1 is an elevation showing one of my improved domes. Fig. 2 is an enlarged detail section on the line 2—2 of Fig. 1. Fig. 3 is an enlarged detail section on the line 3—3 of Fig. 1. Fig. 4 is a section on the line 4—4 of Fig. 3. Fig. 5 is a cross-section of one of the lower horizontal bars. Fig. 6 is a cross-section of the same bar at the point where it is attached to the corner brace, showing the countersunk recess for receiving the screw head. Fig. 7 is a detail plan view of the end of the same bar. Fig. 8 is a cross-section of the upper horizontal bar. Fig. 9 is a detail plan view of one end thereof and Fig. 10 is a section of the same bar at the point where it is attached to the corner piece. Fig. 11 is a transverse section of one of the inclined bars at the point where it is attached to the corner brace, on the line 11—11 of Fig. 3. Fig. 12 is a transverse

section of the same, intermediate its ends. Fig. 13 is a detail plan view of the end of the same bar.

The dome comprises primarily a crown A from which depend inclined bars B directed outwardly. At their lower outer ends the inclined bars are attached to the corner pieces C to which are also attached the horizontal bars of which, in the present instance, there are two sets, an upper set D and a lower set E, forming a panel space between the same.

The inclined bars extending from the crown to the connecting pieces at the outer edge of the dome are channeled, the side flanges B' of the channel giving an apparent depth to the bar when the glass is in place, which adds to the effectiveness of the dome in the matter of appearance. By reason of these side flanges on the inclined bars and the proper shaping of the web of the channel, a sufficient depth is given to the channel itself to permit of the edges of the glass panels F passing in under the bars and being covered from view without the necessity for very accurate fitting or cutting of the glass. As will be seen by reference to Fig. 11, a considerable latitude may be allowed in the glass fitting. These inclined connecting bars have preferably at each end a short slot B² terminating at its inner end in the countersunk portion B³ adapted to receive the head of a cap screw by which the bar is connected to the crown at one end and to the corner brace at the other. By means of such a slot and countersunk structure it will be seen that the bar may be readily attached to and detached from both the crown and the corner brace without entirely removing the cap screws from their sockets, as will be seen by reference to Figs. 3 and 11, where it will be seen that the countersunk portion of the bar projects beyond the surrounding surface of the bar and by this means, when fitted to a corresponding countersink in the corner piece, prevents the bar from slipping away from the corner piece.

The upper horizontal bars D are, as shown in Figs. 2 and 8, angle bars with a 100

flange at both their upper and lower edges. The lower flange D' is for the purpose of catching the lower edge of the dome panels F and holding them in position, while the upper flange D² of these bars is for the purpose of giving stiffness and the appearance of thickness to the bar, thus adding to its effectiveness in the matter of decoration. These horizontal bars have at their ends the same sort of slots and countersunk recesses for connecting them to the corner pieces as have been above described in connection with the inclined connecting bars.

The lower horizontal bars E need not be employed except in those cases where it is desired that the domes shall have a skirt of paneling. These bars, however, are angular channel bars having a suitably shaped flange E' at their lower edge for receiving and supporting the skirt panels G filling in the space inclosed between the lower and upper horizontal bars. These bars also are shown as having the slotted ends with countersunk recesses for receiving the cap screws. It will be noted that the corner pieces are provided with recesses C' of proper shape to receive and hold the horizontal bars.

For the purpose of retaining the skirt panels G, I provide angular retaining strips H which are held by screws to the corner pieces C after the manner shown in Figs. 3 and 4.

It will be seen from the construction above described, that the entire dome, which occupies, when erected, a very large cubic space, may be taken apart in a few moments by turning the clip A' on the crown (shown in dotted lines in Fig. 1) to allow the upper end of the dome panels to fall inwardly and thereafter loosening the cap screws so that the ends of the connecting bars may be slipped from engagement therewith. The panels on the skirt may be removed by lifting them vertically so that they are free from the retaining flange E' of the lower horizontal bar, and then moving them inwardly.

The entire structure may then be packed closely so that a comparatively insignificant space is occupied by the disassembled dome. This is of the greatest value to the retail dealer who is thereby enabled to either cut down the number of storage rooms in which he keeps his wares or, on the other hand, it may enable him to increase the quantity of stock carried, just as he may prefer.

It is further of great saving in the expense of shipment since the cubic space occupied in the carrier is greatly diminished. It will be seen that these advantages are attained without any sacrifice whatever of the beauty or artistic effect of the lamp,

and further that the dome, when assembled, is absolutely rigid and strong.

Having thus described my invention, I claim:

1. A dome for lighting fixtures comprising a crown, inclined connecting bars and horizontal connecting bars, said inclined bars being detachably connected with the crown, means for connecting said inclined bars with the horizontal bars, and means for connecting said horizontal bars with one another.

2. A dome for lighting fixtures comprising a crown, inclined connecting bars and horizontal connecting bars, said inclined bars being detachably connected with the crown, means for connecting said inclined bars with the horizontal bars, means for detachably connecting said horizontal bars with each other, and the horizontal bars being provided with means for supporting panel pieces for the dome.

3. A dome for lighting fixtures comprising a crown, inclined connecting bars, horizontal bars and corner pieces to each of which an inclined bar and two horizontal bars are attached, said corner pieces being detachable from at least two of the bars connected therewith.

4. A dome for lighting fixtures comprising a crown, inclined connecting bars, corner pieces and two sets of horizontal bars, all of said bars being connected to the said corner pieces, said inclined bars being detachably connected to the crown, and said corner pieces being detachably connected to the horizontal bars on at least one side thereof.

5. A dome for lighting fixtures comprising a crown, inclined bars detachably secured thereto and having corner pieces secured to their lower ends, horizontal bars secured to said corner pieces, the connection at one end of each horizontal bar at least being detachable, said horizontal bars each being provided with a flange for supporting the lower edge of glass paneling, and said crown provided with a bracket for holding the upper edge of said panel.

6. A dome for lighting fixtures comprising a crown, corner pieces, horizontal connecting bars detachably connecting said corner pieces together, and additional connecting bars detachably connecting said crown to said corner pieces.

7. A dome comprising a crown and a skirt portion, corner pieces on the said skirt portion and detachable horizontal bars connecting the said corner pieces.

8. A dome comprising a crown and a skirt portion, corner pieces on the said skirt portion and detachable horizontal bars con-

necting the said corner pieces, said bars being angular along their length and having slots in the ends along the angle, the bars being spread in the angle at their junction with the corner pieces to form a seat for the head of an attaching screw.

9. A dome having a crown, corner pieces, and connecting bars detachably securing the crown and corner pieces together, said bars being slotted longitudinally at each end with a flat seat at the end of the slot, said

seat projecting above the surrounding surface of the bars and said corner pieces being provided with cavities to receive said projecting seats on the bars. 15

In testimony whereof, I hereunto affix my signature in the presence of two witnesses.

WILFRID LUMLEY.
